CLAIM

The ornamental design for a wading pool with an inflatable toy, as shown and described.

DESCRIPTION

FIG. 1 is a front perspective view of a wading pool with an inflatable toy showing our new design;

FIG. 2 is a top plan view thereof;

FIG. 3 is a left elevational view thereof, the right side elevational view thereof being identical;

FIG. 4 is a front elevational view thereof; and,

FIG. 5 is a rear elevational view thereof.
